UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

SHOE-SLUGGING MACHINE.

1,114,242.

Specification of Letters Patent.

Patented Oct. 20, 1914.

Application filed June 25, 1906, Serial No. 323,200. Renewed October 20, 1913. Serial No. 796,355.

To all whom it may concern:

Be it known that I, EDWARD ERICKSON, of Boston, in the county of Suffolk and State of Massachusetts, have invented certain new 5 and useful Improvements in Shoe-Slugging Machines, of which the following is a specification.

This invention relates to machines for inserting into the work a series of fasteners 10 which are severed from a continuous strip of stock as fast as they are driven. The form herein shown and described is adapted to that type of shoe machine known as a "slugger", and with slight modification 15 might be used for other classes of work in the manufacture of shoes.

The object of the present invention is to provide a machine of the character referred to which will be capable of operating at 20 high speed without detracting from its efficiency and accuracy, and which will be simple and durable in construction and not liable to minor accidents.

In accomplishing these objects of the invention, I dispense with the complicated feeding mechanisms that have heretofore been employed, provide for the various operative parts being actuated with easy or graduated movements so as to prevent rocking 30 of the machine, and employ simple mechanisms for securing the driving and severing of the fasteners and the feeding of the work.

In the embodiment of the invention which 35 I have illustrated upon the drawings, the fasteners are formed from a metallic strip such as a piece of wire, and the work is fed by laterally moving the embedded end of the strip, after which said embedded end is 40 severed by cutters from the remainder of the strip. The driver takes the form of a bar which is reciprocated and which is mounted upon a laterally oscillatory head so as to have a lateral work-feeding movement 45 at its strip-delivering end. The driver bar has clamps or grippers which intermittently engage the strip to drive its end into the work, and in addition thereto has the cutters which are caused to sever the driven or 50 embedded end of the strip.

In addition thereto, the machine shown is provided with a plate intervening between the work and the fastener-inserting mechanism, and against which the face of the

work is pressed by a jack. This plate has an 55 enlarged and elongated aperture to permit the lateral feeding movement of the driver and to permit the operator to see the face of the work.

Of the accompanying drawings which 60 illustrate one embodiment of the invention Figure 1 is a side elevation of a machine constructed in accordance with this invention. Fig. 2 is a front elevation of the head thereof. Fig. 3 is a reverse side elevation of 65 a portion of the head. Fig. 4 is a sectional elevation of the head on the line 4—4 of Fig. 3. Fig. 5 is a vertical sectional view of the fastener driving mechanism. Fig. 6 is a sectional plan view on the line 6—6 of 70 Fig. 2. Fig. 7 is a vertical sectional view of the fastener driver. Fig. 8 is a horizontal sectional view of the fastener driver. Fig. 9 is a perspective view of one of the cutting members. Fig. 10 is a perspective view of 75 the work-plate. Fig. 11 is a sectional elevation of a portion of the jack depressing mechanism. Fig. 12 is a section on the line 12—12 of Fig. 11. Fig. 13 is a vertical cross section of a portion of the jack depressing 80 mechanism. Fig. 14 is a vertical cross section of the clutch mechanism. Fig. 15 is a plan view of the clutch releasing cam and the brake shoe. Fig. 16 is a vertical longitudinal section of the clutch setting and releasing mechanism.

The same reference characters indicate the same parts wherever they occur.

On the drawings 10 is a base or standard having suitable bearings 11 11 in which is 90 journaled a main power shaft 20. Clutch mechanism, hereinafter described, is provided for driving the shaft. The forward end of said shaft supports a head 15 which contains the fastener driving mechanism 95 and which is adapted to be oscillated about the shaft for feeding the work as hereinafter described.

12 is a work-supporting jack movably mounted in bearings 13 13 and normally 100 held toward the head 15 by a spring 14, and connected by a rod 16 to a treadle 18 pivoted to the base by a stud 19.

17 is a work rest or plate which is adapted to position the work with respect to the 105 fastener driving mechanism by limiting the upward movement imparted to the jack by the spring 14.

21 is a rotatable cap on the top of the jack, (see Fig. 2) upon which the work may be turned or fed.

22 is a work gage pivoted by a stud 23 to 5 a bar 24 which is movably mounted in a suitable bearing on the standard 10. The gage is held against the under surface of the plate 17 by a spring 25 and follower 26 contained in the bar 24 and pressing against 10 the rear side thereof. The bar is provided with rack teeth 27 which intermesh with a gear segment 28 by which the bar and gage may be adjusted and held. Said gear segment is formed on a lever 29 pivoted upon 15 a stud 30 and having a handle 33 which is adapted to be held by a spring 31 in engagement with a ratchet segment 32. By means of the lever 29 the gage 22 may be adjusted in or out so that a heel held against 20 it may be guided thereby in any desired relationship to the fastener driving mechanism. The head 15, which, as previously stated is mounted upon and adapted to oscillate about the shaft 20, is held thereon 25 by a cam disk 34 keyed to the end of the shaft.

35 is a split driver bar which is adapted to be reciprocated longitudinally of its length and transversely of the axis of the 30 shaft 20, and which is held in bearings 36, 36 on the head 15.

37 is a stud affixed to one of the halves of the driver-bar and carrying a roll 38 which occupies a cam groove 39 in the disk 34.

35 The contacting faces of both halves of the driver-bar are grooved along their median line, forming an orifice for the passage therethrough of a continuous strip 50, shown on the drawings as circular wire and 40 supplied from a reel 51 on a bracket 52 attached to the standard 10. The strip 50 is driven successively step by step toward and into the work, is oscillated laterally to feed the work, and the driven portion severed 45 therefrom after having been moved laterally to feed the work. In passing through the driver-bar the strip 50 engages successively a pair of straightening dies 53, 53, a pair of grippers 54, 54 and a split driver 55 having a tubular delivery nozzle 56. (See Figs. 2 and 4.) Of the dies 53, 53 one is affixed to one half of the driver-bar, and the other 50 die is movably installed between the halves and adapted to be adjusted by means of a 55 set screw 58 threaded in the bar.

The driver (see Figs. 4, 5 and 7) comprises the member 55 having the delivery nozzle 56 and a separate removable member 59 loosely fitted upon laterally extending 60 dowels 40, 40. The confronting faces of the members 55 and 59 are grooved for the reception of the strip 50 and constitute gripping jaws by reason of having teeth formed by a series of annular grooves 41.

65 The driver is installed in a chamber 155

formed in the driver-bar 35 and is actuated by means hereinafter described to grip the strip 50 during the downward movement and to release the strip during the upward movement of the bar.

The head 15 is oscillated about the shaft 20 by a lever 42 pivoted upon a stud 43 in a boss on the standard 10. One end of said lever is provided with a roll 44 which cooperates with a cam groove 45 in the disk 34, and the other end of the lever is provided with a curved slot 46 containing the head of an adjustable stud 47. One end of a link 48 is pivoted upon the stud 47, and the other end upon a stud 49 in the head 15, thus forming an adjustable connection between the lever and the head by which the head may be oscillated through an arc of any desired length. A flange 60 on the upper face of the plate 17 occupies a peripheral groove 61 in the bottom of the head and serves to guide and brace the latter.

When the machine is at rest or in normal position the driver-bar 35 is raised and the head 15 is perpendicular as shown in Fig. 2. When the head is in this position the loose member 59 of the driver is forced toward the member 55 by a bar 62 movably installed in a laterally extending guide formed by protuberances 63, 63 on the bar 35. (See also Fig. 6.) One end of the bar 62 abuts against the member 59 and the other end abuts against a perpendicular face of a fixed bracket 64 extending from a standard 10. On the opposite side of the driver, an adjustable abutment 66 in the form of a set screw, and threaded in the head 15, acts through an intermediate block 65 to brace the driver against the thrust of the bar 62. The inner face of the set-screw is parallel to the line of movement of the driver-bar so that when the latter is depressed by the cam 39, the bar 62 and block 65, which cause the driver members 55 and 59 to grip the strip 50, slide relatively to the parallel faces of the bracket 64 and set-screw without relinquishing their pressure upon the driver. The lower end of the driver-bar 35 in being depressed enters an orifice 67 formed in the plate 17 to allow it to approach closely to the work 100 on the jack.

The delivery nozzle 56 of the driver projects slightly below the driver-bar 35 so that when both are depressed the end of the nozzle barely touches the work and if the end of the strip extends below the end of the nozzle it is driven into the work. The cam 39 is so formed that, after causing the driving of the end of the strip 50 into the work, it holds the driver bar motionless relatively to the head 15 for an instant during which the cam 45 causes the lever 42 to swing the head to the left, thus advancing the work, through the agency of the 130

strip 50. Fig. 4 shows the head moved to the latter position. It will be observed that the bar 62 instead of moving laterally with the head is held by the bracket 64 which has 5 a perpendicular groove 68 into which a roller 69 on the bar extends.

The chamber 155 which contains the driver members is so formed as to permit a slight longitudinal movement of the latter 10 therein for a purpose hereinafter explained, and when the bar 62 is in engagement with the driver it overlaps an inclined shoulder 70 formed on the member 59 thus preventing the driver from rising in the chamber during 15 the driving of the strip 50. As shown in Fig. 4, however, the bar 62 is disengaged from the member 59 to permit the severance of the driven fastener from the strip, to which the following description refers.

Each of the members comprising the driver-bar 35 has an outwardly projecting circular boss 71 at the lower end, on which is mounted each of two oscillatory cutters 72 having hardened steel cutting pins 73 adapted to coöperate with each other. (Figs. 2, 4, 5 and 9). The cutting edges of the members 72 are arranged on opposite sides of the line of the strip 50. When the driver bar 35 is depressed to drive the strip into 25 a heel, the members 55 and 59 are depressed so that the lower end of the nozzle 56 may engage the strip as closely as possible to the work for feeding. The cutters are provided with arms 74 which project from the 30 driver-bar in opposite directions and which are adapted to abut against adjustable stop-screws 75 threaded in the lower part of the head 15. When the driver-bar is depressed previous to the oscillating of the head 15, the arms 74 of the cutters are moved as 35 closely as possible to the stop-screws 75 without actually engaging them. Then after the head has been oscillated to feed the work, and the bar 62 withdrawn from the 40 shoulder 70 of the driver, a bulge 76 on the cam 39 depresses the driver-bar slightly farther. The effect of this last movement of the driver-bar is to cause the cutters 72 to be oscillated upon their pivots by the stop-screws 75. This causes the cutting pins 73 to approach each other and sever the strip 45 between them. The cutting edges are so formed and arranged as to cut squarely into the strip leaving the severed portion blunt 50 or square and compressing the new end of the strip so as to form a chisel point. The cutting pins in approaching each other engage the beveled extremity of the nozzle 56 and force it upwardly in its chamber 55 which is slightly elongated as previously 55 stated. The cutters, by thus displacing the nozzle are enabled to cut entirely through and to cover the full cross sectional area of the strip. During the cutting of the 60 strip, the cutters are being depressed about

three sixty-fourths of an inch, the shoe yielding to this extent, so that the end of the slug is severed flush with the surface of the work.

The next movement of the driver-bar 35 is upward, before the head 15 is oscillated back to its former position. The strip 50 is fed relatively to the driver by being gripped and held by the grippers 54, 54 hereinbefore mentioned, during the upward movement of 70 the bar 35. The said grippers are in the form of arms formed on rock-shafts 77, 77 mounted in bearings on the head 15. The free ends of the arms have roughened eccentric faces which are adapted to engage the 75 opposite sides of the strip as already stated. Actuating arms 78, 78 are pinned to the outer ends of the rock-shafts 77, 77 and are normally held apart by a spring 79. The eccentricity of the gripper faces is such as 80 to bind upon and prevent rising of the strip relatively thereto, but to permit descending of the same. The grippers therefore hold the strip when the driver-bar rises thus drawing an additional supply through the 85 dies 53, 53 to replace the fastener previously severed. For operating said grippers, I may employ the following mechanism. 90 80 is a plate having beveled ears or cams 81, 81 on each side (see Fig. 2). The plate has a slot 82 through which a stud 83 extends and is screwed into the driver-bar clamping the plate thereto. The ears 81, 81 are adapted to engage rolls 84, 84 at the free ends of the arms 78, 78 and force them together 95 against the pressure of the spring 79, thus disengaging the gripper arms 54 from the strip 50. The plate 80 as shown in Fig. 2 is set at its highest position in which it does not engage the rolls 84, 84, but it may be 100 clamped at any lower position by the stud 83. When clamped at a lower position the ears 81, 81 in descending engage and displace the rolls 84, 84 thus holding the grippers out of engagement with the strip until 105 the rolls are released by the ears on the up stroke of the latter. During that portion of the up stroke when the ears 81, 81 hold the grippers in inoperative position, the straightening dies 53, 53 hold and carry the 110 strip with them, but when the strip is caught by the released grippers and held stationary it is drawn through the dies and fed relatively to the driver.

Upon the completion of the up stroke of 115 the driver-bar, the head 15 is oscillated to the right, back to its initial position shown in Fig. 2. This movement causes the driver 59 to approach and engage the inner end of the bar 62. It will be remembered that the 120 cutters during their operation raise the driver 59 relatively to the bar 62, so in case the driver remains in that position it is returned to its lower position when the inner end of the said bar engages the inclined 125 130

shoulder 70 on the member 59 previous to clamping that member with the member 55 upon the strip. The driver has, as thus described, a four-way motion by which the feeding of the work in addition to the driving of the slugs or fasteners is accomplished.

The foregoing explanation covers the entire operation of the fastener driving mechanism, but, in describing the work-feeding mechanism, the following explanation of the jack depressing mechanism is necessary. Referring to Figs. 1, 11, 12 and 13, 85 is an actuating cam affixed upon the shaft 20 and co-operating with a roll 86 carried by a lever 87 fulcrumed upon a stud 88 on the standard 10. The free end of the lever 87 is connected by a pin to the upper end of a vertically movable rod 89 mounted in suitable bearings on the standard. The lower end of said rod extends loosely through a hole 91 in one end of a block 90 and is provided with a nut 92 threaded thereon.

93 is a rod extending parallel to and close to the rod 89 and having suitable bearings adapted to permit parallel movement thereof. The rod 93 extends loosely through a hole 94 in the block 90 and is provided with a helical spring 95 compressed between said block and the bearing 96. The rod 93 also extends loosely through a hole 97 in a block 98 connected by a pin 99 to the other end of and extending underneath the block 90. When in normal position the spring 95 pressing on the block 90 holds it against the block 98 and the latter against a fixed stop 101. The lower end of the rod 93 is pivotally connected to one end of a lever 102 which is fulcrumed upon the standard 10 by a stud 103. The other end of the lever extends between two lips 104, 104 of a collar 105 secured upon the jack 12. After the driving of a fastener into the work, and prior to the lateral feeding of the work the cam 85 causes the lever 87 to raise the rod 89. The nut 92 on said rod engages the under side of the block 90 and raises one end thereof, the other end being held down by the spring 95. By reason of the loose fit of the rods in the holes 91 and 94, the block 90 turns on the pin 99 and assumes an angle as shown in Fig. 11. This causes the opposite edges of the hole 94 to take hold upon the rod 93 and continued upward movement of the block 90 causes it to move bodily and to carry the rod 93 with it. The block 98 has an ear 106 which is connected by a spring 107 to a fixed member 108 below it, and as the block 90 rises bodily, raising the pivoted end of the block 98, the downward tension of said spring causes the latter block to assume an angle relatively to the rod 93. The opposite edges of the hole 97 then take hold upon the rod 93 and during the remainder of the upward movement of the rod 89, the blocks

90 and 98 and the rod 93 move therewith as a unit. The movement thus given to the rod 93 is transmitted to the lever 102 which depresses the jack against the pressure of the spring 14. The jack is held in the lower position by the cam 85 thus relieving the pressure of the work against the plate 17 while the cam 45 actuates the head 15 to feed the work. It is while the jack is unlocked that the cutters sever the driven slug. When the blocks 90 and 98 are returned to normal position by the spring 95, the holes 94 and 97 become alined so that the rod 93 may slide relatively thereto when the jack is depressed by means of the treadle 18. Power for rotating the shaft 20 is applied to pulley 110 loosely mounted on the rear end of the shaft. Said pulley normally rotates idly about the shaft but has a plate 111 containing one or more holes 112 which is adapted to engage a bolt 113 contained in a casing 114 mounted upon and attached to the shaft. A spring 115 tends to force the bolt into operative engagement with the pulley but it is normally held out of engagement therewith by a wedge shaped flange 116 formed on a block 117 pinned to one end of a plunger 118. Said plunger is adapted to slide in a bracket 119 on the standard 10 and its other end is connected by a rod 120 to a lever 121 fulcrumed upon the stud 19 upon which the treadle 18 is also fulcrumed. The flange 116 is normally held in engagement with a nose 122 on the bolt by a spring 123 of which one end is attached to the standard 100 and the other to a collar 124 on the rod 120.

The rear end of a treadle 125 fulcrumed upon a pin 126 underlies the free end of the lever 121 and when depressed it rocks said lever so as to cause it to withdraw the flange 116 from the nose 122. Upon releasing of the nose, the bolt 113 snaps into a hole in the plate 111 and is rotated therewith. The casing 114 has two internal diametrically opposite lugs 127, 127 which intervene between two diametrically opposite lugs 128, 128 formed on a collar 129 within the casing and keyed to the power shaft. Two diametrically opposite blocks 130, 130 of rubber or other suitable material are compressed between the lugs 127, 127 and 128, 128. The rotation of the casing transmitted from the pulley by the bolt is in turn transmitted through rubber blocks to the collar 129 and thence to the shaft 20. The blocks serve to absorb the sudden shock of starting the shaft and continue to rotate the same as long as the flange 116 is held out of the path of rotation of the nose 122.

131 is a flange formed on the periphery of the casing 114 and adapted to engage a roll 132 mounted on a lug projecting from the block 117. Said flange is adapted to keep the block and flange out of the path of rotation of the nose 122 when the treadle 125 130

- is released, except when a depression 133 arrives opposite the roll and permits it to approach the casing 114. When the roll does enter into the depression the flange 116 5 moves into the path of the nose 122 and the latter engages and is deflected thereby, withdrawing the bolt from the plate 111 and rendering the machine idle. The momentum of the machine is arrested when the block 10 117 approaches the casing by a brake-shoe 134 carried by said block. Said brake-shoe is mounted upon a lug 135 projecting from the block and engages a flange 136 formed on the periphery of the casing.
- 15 From the foregoing description, it will be apparent that many of the details of construction of the machine may be changed or varied without departing from the spirit and scope of the invention.
- 20 What I claim is:—
1. A machine of the character specified, comprising a laterally oscillatory fastener-driving mechanism, a laterally oscillatory fastener-severing mechanism, and means for oscillating said mechanisms as a unit, said mechanisms and means being timed so that first the driving mechanism drives the fastener into the work and the fastener feeds the work, and second, the severing mechanism severs the fastener after the completion 25 of the feeding of the work.
  2. A machine of the character specified, comprising a stationary work plate, a work support for holding the work against said plate, a fastener driver, means for impelling said driver to force a fastener into the work and to move the embedded fastener laterally to feed the work thereby, and means for severing the embedded fastener.
  3. A machine of the character specified, comprising a work support, a fastener driver, means for reciprocating said driver to embed the end of a fastener strip into the work, means for moving said embedded fastener laterally to feed the work thereby relatively to the work support, and a cutter for severing the embedded end of the fastener at the completion of the work-feeding movement.
  4. A machine of the character specified, comprising a movable fastener driver, means for reciprocating the driver toward and from the work, means for reciprocating the driver transversely to and independently of the said reciprocation toward and from the work to cause the embedded fastener to feed the work, and laterally stationary work-engaging means.
  5. A machine of the character specified, comprising a main shaft, fastener-driving mechanism supported and operated by said shaft for reciprocating a fastener driver to drive a continuous fastener strip into the work, means for holding the fastener driver 60 against longitudinal movement, means for

oscillating said fastener-driving mechanism about said shaft to feed the work, connected by the fastener to the driver, and means for severing the fasteners from said strip.

6. A machine of the character specified comprising a movable fastener driver, means for impelling said driver toward the work, and means for holding said driver against longitudinal movement and swinging it transversely to its longitudinal movement 75 to cause the embedded fastener to feed the work.

7. A machine of the character specified comprising a reciprocating fastener driver for inserting the end of a continuous fastener strip into the work, and means for imparting thereto a four-way motion by means of which the fastener is driven into the work, and the embedded fastener feeds the work laterally.

8. A machine of the character specified comprising a driver having a central aperture for the passage therethrough of a continuous strip of fasteners, means for reciprocating said driver toward and from the work 90 for causing it to drive a series of fasteners successively therein, means for moving said driver transversely of the line of drive after the driving of the fastener, to feed the work, and means for severing each fastener from 95 the strip after said transverse movement of the driver.

9. In a machine of the character described, a fastener driver having a longitudinal passageway for a continuous fastener strip, said driver comprising two cooperative gripping members which are movable laterally for gripping, and movable longitudinally for driving the strip, and a fixed abutment for pressing one of said gripping members toward the other when they are moved laterally.

10. In a machine of the character described, coactive gripping members for driving a strip into the work, a driver bar for carrying said gripping members, said bar having a chamber for said gripping members, said chamber being formed to permit longitudinal movement of the gripping members relatively to the bar, one of said gripping members having a nozzle adapted to engage the work, and cutters adapted to retract said nozzle from engagement with the work and to sever the strip between the nozzle and the work.

11. In a machine of the character described, comprising a reciprocatory driver bar; a driver thereon comprising complementary gripping members, a transverse slide on said driver bar for impelling one of said members toward the other, and means for causing a relative transverse movement of said bar and said slide.

12. In a machine of the character described, comprising a reciprocatory driver 130

- bar; a driver thereon comprising complementary gripping members, a transverse slide on said driver bar for impelling one of said members toward the other, a guide engaged 5 by a projecting end of said slide, and means for effecting a relative lateral movement of said driver bar and said guide to cause the actuation of said slide and the coactive gripping of said members on the fastener.
- 10 13. In a machine of the character described, a reciprocatory driver bar, a driver thereon comprising complementary gripping members, means for longitudinally reciprocating said driver-bar to force a fastener 15 into the work, means for moving said driver bar laterally, and means for causing said gripping members to grip the fastener during the longitudinal movement of the driver bar toward the work and to release said fastener during the lateral movement of said fastener bar.
14. In a machine of the character described, a driver bar, a driver thereon comprising a nozzle and complementary gripping members connected to said nozzle, said driver as a unit being longitudinally movable a small distance relatively to the driver, means for imparting a four-way movement to the driver bar, an automatic cutter mechanism for the fastener, and means for actuating the gripping members to cause them to grip the fastener while the driver bar is moved toward the work, and to release the fastener while the driver bar is being moved laterally, whereby the nozzle and grippers may be moved away from the work to permit the operation of the cutter.
15. A machine of the character specified, comprising a longitudinally reciprocatory driver having a clamp member movable transversely to engage and clamp a fastener strip, means for longitudinally reciprocating said driver, a slide for actuating said clamp member, said slide and said driver 45 being transversely movable one relatively to the other, and means by which said relative movement is effected.
16. A machine of the character specified adapted to drive and sever fasteners from a continuous strip, comprising an oscillatory head, fastener-driving and fastener-severing mechanisms all mounted upon and carried by said head, means for actuating said mechanisms to cause the driving of the fastener, and the feed of the work by the driven fastener, and means for oscillating the head, in combination with a stationary work plate and a jack for holding the work against said plate.
- 60 17. A machine of the character specified comprising an oscillatory head, a split reciprocal driver carried by and movable independently of the head and adapted to engage and clamp a strip extending between the complementary members thereof, a fixed stop, means for oscillating the head, means for reciprocating the driver independently of the head, and means carried by the head and engaging the said stop and adapted to engage the driver and be rendered operative by the oscillation of the head to cause the complementary members of said driver to alternately clamp and release a strip therebetween.
18. A machine of the character specified, comprising co-operative grippers for driving a strip into the work, co-operative cutters for severing the driven strip near the work, said grippers and cutters being operative independently of each other, a carrier for carrying said grippers and cutters toward and from the work, and means adapted to be engaged by said cutters in their movement toward the work for operating them to sever the strip.
19. A machine of the character specified comprising means for driving the end of a continuous strip into the work, means for moving said driven end in a direction substantially at right angles to the line of drive to feed the work, and means for severing the driven end from the strip, all of said operations occurring in the sequence given.
20. A machine of the character specified comprising means for projecting a continuous strip step-by-step toward and into the work, means for drawing laterally the projected end of the strip connected with the work to effect the feeding of the work, and means for severing from the strip each portion which has previously been projected into the work and swung laterally in one direction to feed the work.
21. A machine of the character specified comprising a main shaft, a head oscillatably mounted upon said shaft, means mounted in said head for projecting a continuous strip step-by-step radially with respect to said shaft into the work, and means for oscillating said head and strip through an arc concentric to said shaft to feed the work.
22. A machine of the character specified comprising fastener-driving and severing mechanism adapted to drive and sever from a continuous strip a series of fasteners, and adapted to feed the work step-by-step by means of the strip, means for actuating said mechanism to drive said strip and sever the driven fastener therefrom, and means for actuating said mechanism to effect the feeding of the work.
23. A machine of the character specified comprising a driver adapted to engage and drive a continuous fastener strip into the work, means for actuating said driver to drive the strip step-by-step into the work, means for holding the driver against longitudinal movement and swinging it laterally to draw the end of the strip connecting the work with said driver to feed the work,

and means for successively severing from the strip the portions previously connecting the work with the driver.

24. A machine of the character specified comprising a fixed plate, a jack adapted to support the work against one side of said plate, fastener-driving mechanism having a delivery nozzle on the opposite side of the plate and normally retracted therefrom, there being an aperture in said plate exposing a portion of the work to the fastener-driving mechanism, means for projecting said nozzle through said aperture toward the work to insert a fastener in the work, and means for moving said nozzle transversely to said first movement while in said aperture to cause the inserted fastener to feed the work.

25. A machine of the character specified comprising a reciprocatory driver having clamps adapted to grip and drive a strip step-by-step into the work, a pair of cutters independent of said clamps, movable with the driver, and adapted to sever the strip between the driver and the work, and means for causing the driver to drive the strip by steps of predetermined length toward the work and for causing the cutters after each driving stroke of the driver to sever the driven end from the strip.

26. A machine of the character specified comprising a movable head, a reciprocatory member carried by and movable relatively to the head, a driver carried by said member and adapted to clamp and drive a strip toward and into the work, means adapted to engage said driver when said head is in its initial position and cause the driver to operatively engage the strip, means for moving the driver and said member toward the work when the head is in its initial position, means for moving the head from initial position after the driving of the strip into the work so as to disengage the driver from the means which causes the latter to operatively engage the strip, a pair of stops, and a pair of cutters independent of said driver, and carried by and movable relatively to said reciprocatory member, and adapted when moving with said member toward the work to engage said stops and to be actuated thereby to sever the driven end of the strip near the work.

27. A machine of the character specified comprising a frame, a reciprocatory member or carrier, a driver thereon adapted to drive the end of a continuous strip into the work, means for actuating said member or carrier, cutting mechanism on said member or carrier, and means on the frame for causing said cutting mechanism to sever the driven end of the strip flush with the surface of the work.

28. A machine of the character specified comprising an oscillating head having a

guide, means for transversely oscillating said head, a driver movably held in said guide and adapted to grip a continuous strip, means for reciprocating the driver back and forth in the guide, and means rendered active by the oscillation of the head for causing said driver to alternately grip and release a strip extending therethrough.

29. A machine of the character specified comprising an oscillating head having a guide, means for transversely oscillating said head, a driver normally held in said guide and adapted to grip a continuous strip, means for reciprocating the driver back and forth in the guide, a fixed stop, and means intermediate said driver and said stop adapted to alternately engage with said driver when the latter is oscillated, and so to cause said driver to alternately grip and release a strip extending therethrough.

30. A machine of the character specified comprising means for driving the end of a continuous fastener strip into the work, and for drawing laterally the end of the strip connected with the work to feed the work, and means for severing the driven end from the strip after the work has been fed.

31. In a machine of the character described, comprising an oscillatory head, means for oscillating said head, a reciprocatory fastener driver mounted in said head for feeding a continuous strip step-by-step toward the work and embedding the end thereof in the work, means for holding said driver against longitudinal movement while said head is oscillated, means for swinging said driver and causing the embedded end of the strip to feed the work laterally, and a work plate having an aperture to receive the delivery end of the driver, said plate being provided with means for guiding the lateral movement of said head.

32. In a machine of the character described, comprising an oscillatory head, means for oscillating said head, a reciprocatory fastener driver mounted in said head for feeding a continuous fastener strip step-by-step toward the work and embedding the end thereof in the work, means for holding said driver against longitudinal movement during the oscillation of said head, means for causing the embedded end of the fastener strip connecting the work with said driver to feed the work laterally, and a work plate having an aperture to receive the delivery end of the driver, and a groove and complemental guide, one on the head, the other on the plate, to guide the head during its oscillatory movement.

33. In a machine of the character specified, means for driving step-by-step a strip of indeterminate length, said means being movable laterally for feeding the work, and means for severing the strip near the work while a portion thereof is in the work.

34. In a machine of the character described, fastener-driving mechanism adapted to move laterally of its driving movement to feed the work, and fastener-severing mechanism adapted to be operated by driving movement of said fastener-driving mechanism.
35. In a machine of the character described, a longitudinally reciprocatory and laterally oscillatory member, instrumentalities mounted thereon to drive the fastener and feed the work, and fastener-severing mechanism supported by said member.
36. In a machine of the character described, a tubular nozzle for a strip to be driven into the work, means for reciprocating said nozzle longitudinally to and from engagement with the work, said nozzle having a gripping portion, a gripping member adapted to coöperate with the gripping portion of said nozzle to drive the strip, and cutters for severing the strip close to the work after it has been driven, said nozzle being adapted to recede from the work to permit said cutters to close.
37. In a machine of the character described, coactive gripping members movable toward and from the work for driving a strip into the work, one of said members having a tubular nozzle adapted to engage the work, and cutters for severing the driven strip close to the work, said cutters being adapted to retract said nozzle from the work.
38. In a machine of the character described, coöoperative cutters near the work, a longitudinally movable nozzle for guiding a fastener strip toward the work, the delivery end of said nozzle being movable between and past said cutters, coöoperative grippers movable with said nozzle toward and from the work for engaging and driving the strip, means for opening and closing said grippers, and means for moving said grippers and nozzle toward the work, said cutters being adapted to move the nozzle away from the work and sever the strip between the nozzle and the work.
39. In a machine of the character described, means adapted to drive a strip into

the work, and cutting mechanism adapted to sever the driven strip between said driving means and the work and drive the severed piece farther into the work.

40. In a machine of the character described, means adapted to drive a strip into the work and move transversely to feed the work through the medium of the strip, and cutting mechanism adapted to sever the strip between said driving mechanism and the work after the feeding movement, and to drive the severed piece farther into the work.

41. In a machine of the character described, a carrier movable toward and from the work, means on said carrier for gripping a strip to drive it into the work, said carrier being movable to carry said means transversely to feed the work through the medium of the strip, coöoperative cutters mounted on said carrier, and fixed abutments for operating said cutters, said carrier being adapted to move said gripping means first to drive the strip into the work, and then to feed the work, and to move said cutters so as to sever the strip near the work and to drive the severed piece farther into the work.

42. In a machine of the character described, a fixed abutment, and a driver for a strip of indeterminate length, comprising two coöoperative gripping members, one of said members being movable laterally toward and from said abutment, and the other being between said laterally movable member and said abutment, said abutment being adapted to brace said between member to cause a gripping action of said gripping members when said laterally movable member is moved toward it, said gripping members being movable longitudinally of the strip while gripping the same, to drive the strip.

In testimony whereof I have affixed my signature, in presence of two witnesses.

EDWARD ERICKSON.
